(57) **CLAIM**

The ornamental design for a mounting arm, as shown and described.

DESCRIPTION

FIG. 1 is a front view of a mounting arm, according to the present invention.

FIG. 2 is a back view of the mounting arm of FIG. 1;

FIG. 3 is a top view of the mounting arm of FIG. 1;

FIG. 4 is a bottom view of the mounting arm of FIG. 1;

FIG. 5 is a left view of the mounting arm of FIG. 1;

FIG. 6 is a right view of the mounting arm of FIG. 1;

FIG. 7 is a perspective view of the mounting arm of FIG. 1

FIG. 8 is an environmental view of the mounting arm of FIG. 1; and,

FIG. 9 is another environmental front view of the mounting arm of FIG. 1.

The broken lines represent environment that forms no part of the claim.
